Des. 177,960
Patented June 12, 1956

177,960

MILK CARTON HOLDER OR SIMILAR ARTICLE

Arthur L. Bowans, Denver, Colo.

Application September 12, 1955, Serial No. 37,875

Term of patent 3½ years

(Cl. D58—26)

*Fig. 1.

*Fig. 4.

*Fig. 3.

*Fig. 2.

Figure 1 is a top plan view of a milk carton holder or similar article showing my new design;

I claim:

The ornamental design for a milk carton holder or similar article, as shown.
